(57) **CLAIM**

The ornamental design for a T.V. stand, as shown and described.

DESCRIPTION

FIG. 1 is a perspective view of the T.V. stand of my invention.

FIG. 2 is a front view of the T.V. stand of FIG. 1.

FIG. 3 is a rear view of the T.V. stand of FIG. 1.

FIG. 4 is a top view of the T.V. stand of FIG. 1; and,
FIG. 5 is a side view of the T.V. stand of FIG. 1.

The broken lines in the figures are for environmental purpose only and form no part of the claimed design.
